UNITED STATES PATENT OFFICE

MARTIN FOX, OF CHICAGO, ILLINOIS, ASSIGNOR TO THE SENG COMPANY, OF CHICAGO, ILLINOIS, A CORPORATION OF ILLINOIS

FOLDING BED

Application filed January 26, 1925. Serial No. 4,730.

This invention relates to a folding bed construction which may be used either as a davenport bed or as the more modern type known as a day bed. Among the objects of the invention are: to provide a structure of this kind which will fold compactly within a frame when provided with coil spring sections; to provide a construction which is substantially the same height when used as a bed or as a seat; to provide improved means for mounting the structure in a frame and preventing endwise movement of the sections; to provide means for raising the rear section vertically; to provide operating means for the sections which will enable the outer section to clear the inner one in opening and closing, even though the sections are provided with coil springs; to partially counterbalance the parts in opening and closing; and in general, to provide the construction herein shown and described.

In the accompanying drawing Fig. 1 is an end view partly in section of a day bed constructed in accordance with the principles of this invention; Fig. 2 is a part sectional plan view; Fig. 3 is a view of the bed in closed position omitting one end of the frame; Figs. 4 and 5 illustrate two functions of the spacing and supporting bracket and Figure 6 is a perspective of one of the end brackets.

Among the difficulties in providing a folding bed structure of this kind for coil spring bed sections is to obtain the necessary width as a bed and still make a piece of furniture of desirable width when the structure is closed. Another difficulty is to dispose the coil spring sections within the frame in such a manner that the upper one will not be too high to afford a slightly and comfortable seat. These difficulties are overcome in the present structure by limiting the rear or lowermost section to a substantially vertical movement and by mounting the upper or swinging section to clear the upper edge of the other section as it swings back and forth in opening and closing.

Referring now more particularly to the drawing, a davenport or a day bed frame is provided comprising two ends 1 connected by

a back or back board 2 and by a comparatively narrow front board 3. Although a day bed frame is shown, it is obvious that the same structure could be mounted in a davenport bed frame which differs in having a back which extends above the seat.

Attached to each end of the frame is a supporting cross bar 4 with end brackets 5 in which the bed sections are mounted, and by means of which the folding metal parts are securable as a unit in the frame, to the ends thereof and to the front and back boards.

Two supporting frame structures 6 and 7 are preferably made of angle iron in rectangular form and to each frame is attached in any suitable and well known manner a plurality of coil springs 8 sufficient in length and in resilience to afford a soft spring cushion either for a seat or as a bed.

The lower or inner frame section 6 is mounted on each end upon a pair of pivotally connected levers 9, one pivoted at one end to one side of the frame 6 and the other pivoted at the corresponding end to the cross piece 4. At the other ends of these levers are projections by means of which they make pivotal and sliding connections with the slots 10 and 11 in the frame 6 and cross piece 4 respectively. The resulting action of these crossed levers at the ends of the frame 6 is that of a lazy-tongs and the movement apart of the levers causes a vertical movement of the mattress section or frame 6.

The outer or upper frame section 7 is mounted at its inner end upon links 12 and 13 pivoted on the cross bar 4, the latter link being bent to engage a shoulder 14 of the supporting bracket 5 and there being one of these brackets at each end of the frame, the engagement of the links 13 therewith will prevent endwise movement of the frame 7. The links 12 are connected by means of an equalizer bar 15 rotatable in the frame 7 to equalize the opening and closing movement of the section 7 and preventing uneven or lopsided movement thereof. To support the outer side of the frame 7 in its open position a folding leg 16 is pivoted to the side of the frame at each end and it is connected by means of a link 17 with the link 13 which ex-

tends and folds the leg in accordance with the movement of the frame section 7.

Attached to the outer side of the frame 7 is a front board section 18 which seats, when the structure is closed, on top of the front board 3. A cover 19 is extended over the top of the coil springs 8 of the front section and the front edge of this cover is attached to the top of the front board 18 while the rear is attached to the opposite edge of the frame 7 enclosing the coil springs and presenting a neat appearance.

In order to operate the sections 6 and 7 by the same movement, a link 20 is pivotally connected to the inner end of each link 12 and to the pivotal and sliding extremity of the corresponding lever 9 so that the movement of the upper section 7 will thereupon cause a corresponding movement of the levers 9 in their slots 10 and 11 to raise or lower the rear frame section 6. To assist the movement of the uppermost frame section 7, a spring 21 is connected at each end of the frame to one of the brackets 5 and to a plate 22 secured to the lever 12. Another spring 23 is connected to this plate at one end and through a swinging link 24 to the other bracket 5 at the same end. This latter spring tends to return the frame section 7 within the frame, and when the bed is closed it is loose, the link 24 allowing a free swinging action thereof to permit a movement of the spring without any spring action thereof. The closing operation places the other spring 21 in tension, as shown in Fig. 3, so that it tends to assist in opening the section 7.

Near the back of the frame and attached to each end 1 thereof is a bracket 25 with an upper ledge 26 and a lower inclined portion 27. In the opened position of the bed the rear frame section 6 is intended to fit just between the outermost portions of the brackets on the two ends, as indicated in Fig. 4, which will prevent any rattling or endwise movement of this section. If it is not exactly centered, the engagement with the inclined surface 27 at either end will cause it to be centered when it reaches its uppermost position. When the bed is closed, as shown in Fig. 3, the upper or front sections 7 will rest on top of the ledge 26, as shown in Fig. 5, so that this bracket accomplishes a double function of a rest and an anti-rattler.

Any suitable pad or cushion may be placed on top of the springs, and since it is intended to serve both as a seat and as a bed, it is preferable to provide a double or folding pad having mattress sections 28 and 29 for the front and rear frame sections respectively. These sections may be connected by a hinge 30 and provided with a loose ruffle or valance 31 at the center which, when the bed is closed, as shown in Fig. 3, will fall over the rear board 2. This pad may be secured to the uppermost mattress supporting frame, but it is pref-

erably disconnected therefrom, and in opening or closing the bed the rear section 29 is simply unfolded or folded thereon. It will be observed that the rear angle iron frame 6 turns upwardly while the front one turns downwardly but that the springs 8 are of the same size and the tops of the two sections are intended to be at the same level so that the pads 28 and 29 are the same thickness throughout making a uniform bed or sleeping surface.

To open the bed from its closed position it is necessary only to grasp the upper frame section 7 or any portion thereof and pull or raise it lightly whereupon it will swing outwardly upon the links 12 and 13, the extremities of which are parallel, and this action will cause the raising of the rear frame section 6. The mattress pad 29 is then swung backwardly over the rear mattress support and the bed surface is ready for use. To close the bed this action is simply reversed.

I claim:

1. In a folding bed, a pair of mattress supporting sections, a support, means for supporting one section on the support to swing laterally with respect to the other, separate supporting means for the said other section comprising crossed links pivoted together intermediate their ends and having pivoted and sliding connections with both said other section and the support which also limit it to a vertical direction, and a single connection at each end between the supporting means of the two sections to positively raise or lower the second of said sections accordingly as the first section is moved laterally away from or toward the second section.

2. In a folding bed, a pair of bed sections disposed one above the other, links connecting the bed frame and the upper section to swing it laterally at one side of the other section, a pair of crossed levers pivoted together at the crossing point at each end of the other section, one having a pivotal and the other a sliding connection therewith, a frame having a sliding and a pivotal connection respectively with the same levers, and a link connecting a swinging link of the first section with a lever of the lower section for positively raising and lowering the lower section in a vertical direction when the upper section is swung laterally upon its links.

3. In a bed, the combination with a frame, of a main bottom member vertically reciprocable in said frame, an extension bottom member adapted to be positioned above said main bottom member in said frame, a pair of parallel links at each end of said extension member connecting said frame with said extension member to permit swinging said extension member out of said frame to one side of said frame, a pair of crossed links pivotally connected to one another medially of their lengths at each end of

said main bottom member, one end of one of the links of each crossed pair having its upper end pivotally connected to said main bottom member and its other end slot and pin connected to said frame, one end of the other link of each crossed pair having its lower end pivotally connected to said frame and its other end slot and pin connected to said main bottom member, and means connecting said crossed links with said parallel links to cause said crossed links to be operated with said parallel links.

4. In a bed, the combination with a frame, of a main bottom member vertically reciprocable in said frame, an extension bottom member adapted to be positioned above said main bottom member in said frame, a pair of parallel links at each end of said extension member connecting said frame with said extension member to permit swinging said extension member out of said frame to one side of said frame, a pair of crossed links pivotally connected to one another medially of their lengths at each end of said main bottom member, one end of one of the links of each crossed pair having its upper end pivotally connected to said main bottom member and its other end slot and pin connected to said frame, one end of the other link of each crossed pair having its lower end pivotally connected to said frame and its other end slot and pin connected to said main bottom member, and a pair of connecting links, each of said connecting links connecting one of the links of a pair of parallel links with one of the links of the adjacent pair of crossed links to permit simultaneous operation of said parallel links and said crossed links.

5. In a bed, the combination with a frame, of a main bottom member vertically reciprocable in said frame, an extension bottom member adapted to be positioned above said main bottom member in said frame, a pair of parallel links at each end of said extension member connecting said frame with said extension member to permit swinging said extension member out of said frame to one side of said frame, a pair of crossed links pivotally connected to one another medially of their lengths at each end of said main bottom member, one end of one of the links of each crossed pair having its upper end pivotally connected to said main bottom member and its other end slot and pin connected to said frame, one end of the other link of each crossed pair having its lower end pivotally connected to said frame and its other end slot and pin connected to said main bottom member, and a connecting link at each end of said frame connecting the lower end of one of the links of a pair of parallel links with the lower end of one of the links of the adjacent pair of crossed links to permit simultaneous operation of said parallel links and said crossed links.

6. In a bed, a frame having at each end a base bar, a main bottom member, an extension bottom member, similar connections at each end between the said bottom members and the frame each comprising a pair of parallel bars pivotally connected with the extension bottom member and with the lower base bar of the frame, a support for the outer portion of the extension member whereby it can be supported as an extension level with the said bottom member, a pair of medially pivoted crossed bars pivoted between the main bottom member and the base bar of the frame, one of the cross bars having one end carried by a fixed pivot in the main bottom member and the other end engaging a slotted portion of the base bar and the other crossed bar having one end carried by a fixed pivot in the base bar and the other end engaging a slotted portion in the main bottom member, a link pivoted at the lower pivot end of one cross bar which has a slotted connection with the base bar, the other end of said link being pivoted to one of said parallel bars near its lower end, whereby the movement of the extension bottom over onto the frame will cause this link to swing the connected cross bar and depress the main bottom member, to permit the extension bottom to occupy the normal upper position of said bottom member with the bottom members superposed, and return movement of the extension bottom to open position will return the other bottom member to normal open position.

7. In a bed, the combination with a frame, of a main bottom member, an extension bottom member, a pair of parallel links at each end of said extension member connecting the lower end of said frame with said extension member to allow swinging said extension member to one side of said frame, a pair of crossed links medially pivotally connected to one another at each end of said bottom member and each pair connected to the lower end of said frame and to said main bottom member by means allowing raising said bottom member relative to said frame and links connecting said parallel links with said crossed links to cause said main bottom member to be raised when said extension bottom member is swung to one side.

8. In a bed, the combination with a frame, of a main bottom member, an extension bottom member, a pair of parallel links at each end of said extension member connecting the lower end of said frame with said extension member to allow swinging said extension member to one side of said frame, a pair of crossed links medially pivotally connected to one another at each end of said bottom member connecting the lower end of said frame with said main bottom member by means whereby operation of said crossed links causes elevation or depression of said

main bottom member relative to said frame and a link at each end connecting one of the links of a pair of parallel links with one of the links of the adjacent pair of crossed links 5 to cause simultaneous operation of the crossed links with the parallel links.

9. In a bed, the combination with a frame, of a bed bottom member, a pair of crossed links medially pivotally connected to one another at each end of said bottom member and each pair having means connecting it pivotally and slidably with the frame and with the bottom member whereby the bottom member may be raised or lowered relative to said 10 frame, a pair of parallel links at each end of said frame having their lower ends respectively pivoted to the frame, one of said parallel links at each end operatively connected to one of said crossed links and a connecting member at each end connecting said 15 parallel links to one another so that the operation of one parallel link will cause the operation of the second parallel link and in turn cause the raising or lowering of said 20 bottom member.

10. In a bed, the combination with a frame, of a bed bottom member, a pair of crossed links pivotally connected to one another medially of their lengths at each end of said 25 bed bottom member, one end of one of the links of each crossed pair having its upper end pivotally connected to said bottom member and its other end slot and pin connected to said frame, one end of the other link of each 30 crossed pair having its lower end pivotally connected to said frame and its other end slot and pin connected to said bottom member, a pair of parallel links at each end of 35 said frame, said parallel links each pivotally connected at its lower end to said frame, one parallel link at each end operatively connected to one link of a pair of crossed links and a connecting member connecting all of 40 said parallel links whereby the operation of 45 one of them will cause the operation of all the others and simultaneously the raising or lowering of said bottom member.

11. A foldable davenport bed comprising a fixed main frame, inner and outer bed-sections movable relatively thereto, an inner bed-section lever-system mounted upon the main frame for raising and lowering the inner bed-section, parallel links pivotally connecting the outer bed-section with the main frame, 50 some of said links being provided with transversely extending arms, a resilient member connected to one end of each of said arms and tending to elevate said outer bed-section, and the other ends of said arms being link-connected with the inner bed-section lever-system, whereby the latter lever-system is rendered movable by manipulation of said 55 outer bed-section.

MARTIN FOX.
